UNITED STATES PATENT OFFICE.

ROBERT ZAHN, OF PLAUE, GERMANY; ALFRED BIETZSCH ADMINISTRATOR OF SAID
ZAHN, DECEASED.

SHUTTLE EMBROIDERING-MACHINE.

1,137,826.

Specification of Letters Patent.

Patented May 4, 1915.

Application filed January 25, 1913. Serial No. 744,203.

To all whom it may concern:

Be it known that I, ROBERT ZAHN, a subject of the German Emperor, residing at Plauen, in Vogtland, in the Kingdom of 5 Saxony, Germany, have invented certain new and useful Improvements in Shuttle Embroidering-Machines, of which the following is a specification.

With shuttle embroidering machines of 10 the latest type, in which the shuttles have their filling openings arranged sidewise and bear on the raceway with one of their solid surfaces, it is obvious, that in order to positively guide the shuttles, the borders or projecting bars at the sides of the raceway must snugly bear against the sides of the shuttle, which, however, with the hitherto used structure of the shuttle is not possible, as there must be sufficient free space around 15 the shuttle, to accommodate the thread of the loop, which often is quite thick and through which the shuttle must slip through. This free space, however, gives the shuttle so much freedom of lateral movement that 20 during its operation instead of traveling in a straight rectilinear line it swings to and fro and consequently its pointed end misses the loop of the needle thread through which it has to pass. The result is that a stitch is 25 lost, and if this happens frequently the work is spoiled. Obviously with the large size 30 embroidering machines, now commonly in use, and in which about a thousand needles are simultaneously in operation, the constant missing of stitches is unavoidable 35 when the hitherto used construction is adhered to.

The object of my invention is to remedy this evil, which I accomplish by the improvement constituting the subject of this 40 invention.

In the accompanying drawing similar reference characters denote corresponding parts and Figure 1 is a perspective view of 45 my new shuttle and Fig. 2 is a rear view of two slightly inclined raceways for the shuttles; Fig. 3 is a side view of a raceway and shuttle and Fig. 4 a cross section on line z—z of Fig. 2.

In the drawing A, A denote the stationary 50 raceways, which in well known manner are arranged slightly inclined and which are provided with lateral borders or guide bars a', a'.

b denotes my improved shuttle, which has 55 its filling opening and cover or lid b' arranged sidewise, so that when in operative position, this opening faces one of the guide plates, as a'. The shuttle is also so constructed, that one of its solid surfaces, as b², 60 serves as a bearing surface, in other words the shuttle bears on the raceway, not with the narrow edges surrounding the filling opening, but with a solid surface, which is formed as a straight or plane surface. 65 With such structure of the shuttle and such arrangement thereof in the raceway, it has been found that the shuttle, during its reciprocal movement, has the tendency to swing sidewise, because of the free space 70 around the shuttle, which necessarily must be provided to accommodate the thread of the loop, which often is quite thick and through which the shuttle is adapted to slip 75 through. Such tendency to swing sidewise, results frequently in the shuttle point missing to pass through the loop and consequently in the loss of a stitch. To obviate 80 this drawback, the rounded surface of the shuttle, which faces the longitudinally extending and projecting bar a², has a longitudinally extending undercut portion b³, which forms a straight or plane edge, adapted to snugly bear on the projecting bar or plate a² and in coöperation with the latter 85 to form a positive rectilinear guide for the shuttle.

What I claim and desire to secure by Letters Patent is:

1. The combination with a shuttle raceway, 90 having a longitudinal guide member, of a shuttle having its filling opening in one side, a curved surface on its opposite side which surface is undercut at its lower edge and forms a flat longitudinal shoulder or edge 95 adapted to coöperate with said guide member and to form a positive rectilinear guide for the shuttle.

2. A shuttle having a flat solid bottom, a
filling opening in one side, a curved surface
in the opposite side which surface is under-
cut at its lower edge and forms a flat longi-
5 tudinal shoulder or edge serving as a guide
for said shuttle.

In testimony whereof I affix my signa-
ture in presence of two witnesses.

ROBERT ZAHN.
